UNITED STATES PATENT OFFICE.

WILLROD A. BRULÉ, OF WALPOLE, MASSACHUSETTS.

FRICITION CORE-PICKER.

1,069,670.

Specification of Letters Patent.

Patented Aug. 12, 1913.

Application filed October 3, 1912. Serial No. 723,695.

To all whom it may concern:

Be it known that I, WILLROD A. BRULÉ, a citizen of the United States, residing at Walpole, in the county of Norfolk and State of Massachusetts, have invented a new and useful Improvement in Friction Core-Pickers, of which the following is a specification.

This invention relates to what I have termed a friction core picker, and the object 10 of the invention is an attachment for picker sticks, which will not chip off through constant impact with the shuttle, and which will wear for a maximum amount of time, and which if necessary can be reversed thereby 15 greatly increasing the life and usefulness of the device.

The invention consists of the novel features of construction hereinafter described, pointed out in the claims and shown in the 20 drawing in which,

Figure 1 is a sectional side elevation. Fig. 2 is a face view, partly broken away and partly in section. Fig. 3 is a side elevation, partly broken away and in section illustrating a holding attachment. Fig. 4 is a transverse section upon the line 4—4 of Fig. 3. Fig. 5 is a plan view of the blank from which the holder is formed.

In these drawings, 1 represents the picker 30 stick to which is secured a pad or buffer formed of a plurality of rubber strips 2. I have shown these strips as four in number, although this number may be increased or decreased as found advisable. These strips 35 are secured to the stick by means of screws 3, and to guide or center said screws I embed between two of the intermediate strips suitable washers 4. Each strip is provided with a circular central opening thereby providing 40 in the completed pad a suitable recess for the reception of the friction core 5. This core is formed of a suitable strip of canvas coated with rubber and then rolled in the form of a cylinder and suitably vulcanized. 45 This forms a cylindrical core of rubber and canvas and in preparing the same, I prefer to cut the canvas upon the bias.

The above description describes the invention in its most simple form, and one in 50 which it is attached in a fixed position to the picker stick. In Figs. 3 and 4, I have illus-

trated the same device adjustably connected to the stick. In these figures 6 represents a 55 slideable casing which carries loops 7, in which the pad of rubber strips 4 are inserted, said loops holding the ends of the pad and the inner face of the pad being supplied with a metal base 9, the rubber strips, the base 9 and the loops 7 being all connected by means of suitable rivets 10, which 60 also pass through the washers 4 and at the place of the screws 3. The casing 6 may also be provided with a set screw 8 so that it can be locked in a different position upon 65 the picker stick.

In Fig. 5, I have shown the blank from which the holder is constructed and which consists of a body portion A cut out at the ends and also provided in said cut-out portion with short longitudinal slots thereby 70 producing end flaps B. At each end and upon opposite sides of the end flaps are left the arms C. By folding the body portion as indicated at the dotted lines and overlapping the flaps B, the casing 6 is produced, 75 and by bending the arms C at the dotted lines so that the arms at one end of the blank will lap over those at the opposite end the flaps 7 are formed. But it will be understood 80 that the construction of the friction core or the picker is the same no matter what means may be employed for securing it to the picker stick. I do not desire to be limited to any particular means although the form shown in Figs. 3 and 4 has as many 85 advantages and is my preferred form of holder where it is desirable to attach the picker to the stick so that it may be readily adjustable along the stick.

What I claim is:—

1. A picker consisting of a plurality of rubber strips, said strips being centrally cut out to form a central opening, and a cylindrical core of vulcanized canvas and rubber adapted to fit snugly within said opening. 95

2. A picker consisting of a plurality of rubber strips centrally cut-out, metal washers embedded between two of said strips and adjacent the ends of the strips, and a core formed of a canvas strip coated with rubber, 100 rolled into the form of a cylinder and vulcanized, the ends of said core being flush

with the outer and inner faces respectively of the picker.

3. The combination with a picker stick, of a metal casing slidably fitting said stick, 5 loops carried by the casing, a picker formed of elastic strips, laid one upon the other, and the end portions of which are secured in

said loops, said strips being centrally cut out, and a core of canvas and rubber snugly fitting said central cut out portion.

WILLROD A. BRULÉ.
